John P. Ridings, of Hillsborough, Ohio

Letters Patent.

The Schedule to, in these Letters Patent, and making part of the same, containing a description in the words of the said John P. Ridings himself of his improvement, in Threshing of Clover seed.

To all to whom these presents shall come: Be it known that I, John P. Ridings, of Hillsborough, in the County of Highland and State of Ohio, have invented a new and useful improvement in threshing of clover seed, and that the following is a full and exact description thereof: first: the frame to be of any form to produce the desired effect, the cylinder to be made of heads with the grain of the wood changed every thickness to any size to suit the machine with a shaft through it to run on bushes or cylinder rails with a strap pully on one end of shaft and feeder pully on the other, the shelving or threshing floor to be made solid or caled together with fellows on each side to keep it from springing or warping to extend far enough to carry the feeder & feeders of feeder run in fellows of shelving, and is supported by them, the cord or strap passes round the head on cylinder shaft and round feeder pully & causes the feeder to run which draws in the seed & hull between the cylinder and shelving, the shelving is suspended at the feeder end of shelving by a crop piece made fast to top of frame, or the crop piece can be left portable with loops passing over it, and screwed to the fellows of shelving on each side, the regulating screws pass through the loops on the upper side, and the ends of screws strike against the crop piece, on top of frame, which enables you to set the shelving closer to the cylinder or wider just as is necessary, the spring to force the shelving to cylinder is four and two is made fast to top of frame, to force the top of the shelving & feeder close on to the cylinder the other two are made fast on the back of frame for to force the shelving close against the regulating stops and screws, the stops are fast to frame & the regulating screws pass through the stops & strike against the proques in the lower end of shelving which forces the shelving to any distance from the cylinder to any distance that is necessary, the seed and hull is put on feeding board which conveys it down to cylinder and feeder which causes it to pass

between cylinder and shelving which separates the seed from the hull - the seed after leaving the shelving falls through a separating screen and comes out at the back of machine, the hull or chaff, passes on over screen and comes out under feeding board or table on the opposite side of machine by reason of dividing shorts - the cylinder is clothed with castings - the castings to be cast in plates of any size to suit the size of cylinder with small projecting teeth or points of an eighth of an inch or more - the shelving is clothed with the same kind to be fastened on with screws, and when in operation the teeth or points a coming in contact with each other cut the hull of the seed perfectly clean without injuring of the seed in the least, the screws can be made of tin or sheet iron with holes punched through to let the seed fall through - this machine can be made of any size to suit the Country or quantity of threshing to run or to be turned by hand or by horse or horses, this machine may also be clothed with sheet iron punched so as to raise projecting beads, on the one side and clothe the cylinder & shelving with it and the beads or teeth coming in contact get it out very well but it is not so durable as the castings - the machine when reduced to be turned by hand must be double gear either by cog or strap or else the speed of cylinder will not be great enough to get out the seed perfectly clean when reduced to be turned by hand, the frame can be to suit the convenience of the machine - What I claim as my own invention and not previously known in the above described machine is the the manner of applying the spring to the shelving so as to admit of the shelving giving way when needed - like wise the loops & regulating screws on the principal which they act like in the separating screen to divide the seed from the chaff & the cast plates in the form I send you in the middle.
